US0D1048379S

(12) **United States Design Patent** (10) **Patent No.:** **US D1,048,379 S**
(45) **Date of Patent:** ** *Oct. 22, 2024

(54) **HEADGEAR AND YOKE ASSEMBLY**

(71) Applicant: **Fisher & Paykel Healthcare Limited**,
Auckland (NZ)

(72) Inventors: **Silas Sao Jin Siew**, Auckland (NZ);
Thomas Mark Richardson, Auckland (NZ); **Jonathan Mark Downey**,
Auckland (NZ); **Janine Elizabeth Collins**, Auckland (NZ); **Chris Onin Limpin Hipolito**, Auckland (NZ); **Steve Thomas**, Auckland (NZ); **Priyanka Ferdinand Pereira**, Auckland (NZ);
Matthew Aaron Bradley, Auckland (NZ)

(73) Assignee: **Fisher & Paykel Healthcare Limited**,
Auckland (NZ)

(*) Notice: This patent is subject to a terminal disclaimer.

(**) Term: **15 Years**

(21) Appl. No.: **29/874,932**

(22) Filed: **Apr. 26, 2023**
